UNITED STATES PATENT OFFICE.

BURT NEULON PIERCE, OF INDIANAPOLIS, INDIANA.

CARBURETER-HEATER.

1,032,937.

Specification of Letters Patent. Patented July 16, 1912.

Application filed January 27, 1910. Serial No. 540,323.

To all whom it may concern:

Be it known that I, BURT NEULON PIERCE, of Indianapolis, county of Marion, and State of Indiana, have invented a certain 5 new and useful Carbureter-Heater; and I do hereby declare that the following is a full, clear, and exact description thereof, reference being had to the accompanying drawings.

10 The object of this invention is to provide a practical heater in combination with a carbureter, and an internal combustion engine for preventing the mixture within the carbureter or throttle valve from freezing, 15 or preventing its non-vaporization.

The chief feature of the invention consists in utilizing the exhaust gases from the cylinder of the engine for furnishing the heat. In the second place a heater is attached to the carbureter into which the hot air is introduced, and a throttle valve passageway extends through said heater from the carbureter to the engine and the throttle valve is in said passageway and not in the 20 carbureter proper. Also, the air for the carbureter is heated by said heater before entering the carbureter, so that the fuel will not have its temperature reduced when around the needle or nozzle valve sufficiently 25 to prevent vaporization. The air for the carbureter enters through a pipe that leads to a drum surrounding the hot air chamber in the heater into which drum the air enters from the outside.

30 Another feature of the invention consists in providing a valve for regulating the admission of exhaust gases from the cylinder of the engine to the heater, and particularly in means for connecting said valve with the 35 throttle valve, so that the two will be held in certain relation to each other and the heating valve will be actuated at the same time that the throttle valve is actuated.

The nature of the invention will be understood from the accompanying drawings and the following description and claims.

In the drawings: Figure 1 is an elevation of the device; Fig. 2 is a horizontal section on the line 2-2 of Fig. 1; on a larger scale; Fig. 3 is an enlarged section on the line 3-3 of Fig. 1; Fig. 4 is a vertical section on the line 4-4 of Fig. 2 in slightly modified form; Fig. 5 is a vertical section on the line 5-5 of Fig. 4, and: Fig. 6 is an 55 elevation of the combined carbureter and

heater as shown in Fig. 1 but on a larger scale.

There appear in Fig. 1 four cylinders 10 of an internal combustion engine to which fuel supply tubes 11 lead from the throttle 60 heating chamber 12 and carbureter 13.

14 is the exhaust tube leading from the cylinders and conveying the combusted gases therefrom, and a portion of said gases are conducted from the pipe 14 by the flexible 65 tube 15 to the heater 12, as indicated in Figs. 2 and 4.

The carbureter 13 may be of any type and the details of its construction herein are for that reason not explained.

70 16 is the fuel supply tube, and hot air comes from the heater through the tube 17 to supply the carbureter with air, and the gas mixed and formed in the carbureter enters the lower end of the throttle chamber 75 19 and passes thence to the cylinder of the engine. The throttle chamber is closed by a throttle valve 20 mounted on the shaft 21, which carries a throttle lever 22.

75 The heating mechanism which is the chief novel feature, consists of a heating chamber 25 surrounding the throttle chamber 19 and to which the exhaust gas tube 15 leads through a short tube 26, in which the regulating valve 27 is mounted, as seen in Fig. 4, 80 for controlling the supply of hot exhaust gas. The valve 27 is on a valve stem or rod 28 extending out of the tube and having on it a crank arm 29 which has a longitudinal slot 30 with which a connecting rod 31 is 85 slidably connected by the connection 32, and said connecting rod is pivotally connected with the throttle lever so that the action of the throttle lever will cause a corresponding actuation of the heat regulating valve 27 90 for regulating the admission of heating gas. The spring 33 running from one end of the crank arm 29 to an arm 34 tends to maintain the valve 27 normally open. The arm 34 is secured on a threaded sleeve 35 that screws 95 on the tube 26 and has a contracted outer end with a conical opening that overlaps the end of the copper tube 15, which is stretched over the conical nipple 36, which is held in place by the sleeve 35 against the end of the tube 26, as shown in Fig. 4.

100 The valve construction just described is so arranged that usually when the valve 27 is opened, as shown in Fig. 4, the throttle valve will be nearly closed, and this is the 105 11

position of the valves when running at low speed. At that time, since the passageways around the throttle valve are so slight, the rush of air thereby chills and prevents vaporization of the fuel. The tendency to freeze is greater running at low speed than running at high speed, as the opening is smaller around the throttle valve. Hence it is desirable at that time to have the valve 27 open to its limit, as shown in Fig. 4. When the speed is greater, the passageways around the throttle valve 20 are not only greater but the gases passing from the cylinders through tubes 14 and 15 are extremely hot, and only a small portion of them need therefore be deflected through tube 15 into the chamber 25. Hence with such a correlative arrangement of the valves 27 and 20, the valve 27 will be nearly closed when the throttle valve 20 is fully opened. While this is the general rule for the operation of said valve, still the construction is such that the relative position of the valves may be modified as is required at times. This result is obtained by the following arrangement. The throttle lever 22 is rigidly attached at its outer end to the rod 31. Loosely mounted on the outer end of member 31 is the member 32, which is held in place by the duplicate nuts 131. Member 32 carries a projecting knol or pin not shown, which has a sliding fit in the slot 30 of the lever 29. The spring 33 tends always to pull the lever 29 in the direction of the outer end of the lever 31, so that member 32 is pressed against the inner nut 131. It will be apparent that by loosening the outer nut of the pair 131 and adjusting the inner one the active length of the arm 31 will be changed, and consequently the relative position of the valves 20 and 27 will be altered. From the throttle lever 22 suitable means is extended whereby it is conveniently operated.

The exhaust gases pass into the lower part of the chamber 25 and around the throttle chamber 19 and out through a tube 38 which leads from the lower end of said chamber 25, and a branch tube 39 that leads from the upper end of the chamber to the tube 38. By having two outlets from the heating chamber, one at each end, the hot gases are made to pass through the chamber at reduced speed and come into immediate contact with the entire length of the duct 19 within the chamber. The tube 38 is bolted on to the casing 25 by bolts 40 and from that tube the exhaust tube 41 extends, see Fig. 6. The air which enters the carbureter through the tube 17 is heated by coming in through the hot air drum 18, which surrounds the exhaust gas tube 38. As seen in Fig. 2, the open end of the hot air drum 18 is next to the casing 25, which is warm, so that the air as it enters the drum is heated

and within the drum it is further heated by the exhausted gases in the tube 38 sufficiently to take the chill off the air and prevent possible freezing of the mixture at the fuel inlet or valve of the carbureter, or at least prevent non-vaporization.

The manner of securing the flexible tube 15 to the exhaust tube 14 is indicated in Fig. 3. The end of the flexible tube 15 is stretched over a nozzle 50 that tapers in both directions, one end fitting in a tapering hole in the pipe 14. A sleeve 51 surrounds the outer tapering end of the nozzle and tube 15 and has arms 52 extending therefrom to one of which a strap of metal 53 is secured at one end, and then it passes around the tube 14 overlapping the legs 54 of a bracket and under the other arm 52 of the sleeve 51 and back again over the bracket arms. The bracket 55 has a set screw 56 in it which screws down against the metal strap and holds it in place and tightens it, and by means of the strap draws the sleeve 51 and nozzle 50 tightly toward the tube 14.

While I have herein shown and particularly described the preferred embodiment of my invention, I do not mean to limit myself to the precise construction and arrangement as herein set forth, but

Having thus described my invention, what I claim as new and desire to secure by Letters Patent is:

1. The combination of a cylinder of an engine, a carbureter, a heater combined with the carbureter through which the throttle passageway extends to the cylinder of the engine, a throttle valve for regulating said passageway in the heater, a chamber in the heater surrounding the portion of the passageway containing the throttle valve, means for conveying the exhaust gases from the cylinder to said heating chamber, a valve for regulating the admission of said gases to said heating chamber, and an adjustable means connecting said valve and the throttle valve, whereby the desired relative positions of the two valves may be established and both operated simultaneously.

2. The combination of a cylinder of an engine, a carbureter, a heater combined with the carbureter through which the throttle passageway extends to the cylinder of the engine, a throttle valve for regulating said passageway in the heater, a chamber in the heater surrounding the portion of the passageway containing the throttle valve, means for conveying the exhaust gases from the cylinder to said heating chamber, a valve for regulating the admission of said gases to said heating chamber, an adjustable means connecting the valve for said heating chamber and the throttle valve, and a spring tending to close the valve for said heating chamber.

3. The combination of a cylinder of an engine, a carbureter, a heater combined with the carbureter through which the throttle passageway extends to the cylinder of the engine, a throttle valve for regulating said passageway in the heater, a chamber in the heater surrounding the portion of the passageway containing the throttle valve, means for conveying the exhaust gases from the cylinder to said heating chamber, an outlet passageway from said heating chamber, a drum surrounding said passageway adjacent the heating chamber with an opening therein for the admission of air, and an air tube leading from said drum to the carbureter for supplying warm air to the carbureter.

4. A device of the character described comprising an internal combustion engine, a carbureter, a duct from said carbureter to said engine, throttling means for said duct, means for heating the explosive mixture furnished by said carbureter, and means operable simultaneously with said throttling means to regulate said heating means.

5. In combination an internal combustion engine, a carbureter for supplying explosive fluid, a heater for heating said explosive fluid, means governing the supply of explosive fluid to said engine, means for regulating said heater and a manually operated device for simultaneously actuating the two first aforesaid means.

6. In combination an internal combustion engine, a carbureter for supplying explosive fluid, a heater for heating said explosive fluid, a duct for supplying exhaust gases from said engine to said heater, means governing the supply of explosive fluid to said engine, means for regulating said heater and a manually operated device for simultaneously actuating the two first aforesaid means.

7. A device of the character described comprising an internal combustion engine, a carbureter, a duct from said carbureter to said engine, throttling means for said duct, means for heating the explosive mixture furnished by said carbureter, from the exhaust gases of said engine, and means operable simultaneously with said throttling means to regulate said heating means.

8. In combination an internal combustion engine, a carbureter for supplying explosive fluid, a heater for heating said explosive fluid, means governing the supply of explosive fluid to said engine, means for regulating said heater, and interlocked manually controlled operating devices for said two means.

9. In combination an internal combustion engine, a carbureter for supplying explosive fluid, a heater for heating said explosive fluid, means governing the supply of explosive fluid to said engine, means for regu-

lating said heater, and interlocked adjustable manually operated devices for said two means.

10. In combination an internal combustion engine, a carbureter for supplying explosive fluid, a heater for heating said explosive fluid, means governing the supply of explosive fluid to said engine, means for regulating said heater, and interlocked operating devices for said two means to operate them inversely whereby as one means increases the supply of explosive fluid the other means decreases the heating effect.

11. In combination an internal combustion engine, a carbureter for supplying explosive fluid, a heater for heating said explosive fluid, means governing the supply of explosive fluid to said engine, means for regulating said heater, and interlocked adjustable operating devices for said two means to operate them inversely whereby as one means increases the supply of explosive fluid the other means decreases the heating effect.

12. In combination an internal combustion engine, a carbureter for supplying explosive fluid, a heater for heating said explosive fluid, means governing the supply of explosive fluid to said engine, means for regulating said heater, interlocked operating devices for said two means, and mechanism whereby the relative positions of said means with respect to each other may be adjusted.

13. In combination an internal combustion engine, a carbureter for supplying explosive fluid, a heater for heating said explosive fluid, a duct for supplying exhaust gases from said engine to said heater, means governing the supply of explosive fluid to said engine, means for regulating said heater, interlocked operating devices for said two means, and mechanism whereby the relative positions of said means with respect to each other may be adjusted.

14. In combination with an internal combustion engine of a carbureter for supplying explosive fluid, means for heating said carbureter, and means for increasing the heat supply to said heating means as the supply of explosive fluid decreases, and decreasing the heat as the supply of explosive fluid increases.

15. In combination an internal combustion engine, a carbureter for supplying an explosive fluid, a heater for heating said explosive fluid, means governing the amount of explosive fluid supplied to said engine, means for regulatng said heater and an operating device for simultaneously actuating the two first aforesaid means.

16. In combination an internal combustion engine, a carbureter for supplying an explosive fluid, a heater for heating said explosive fluid, a duct for supplying exhaust

gases from said engine to said heater, means for governing the amount of explosive fluid supplied to said engine, means for regulating said heater, and an operating device for simultaneously actuating the two first aforesaid means.

17. In combination an internal combustion engine, a carbureter for supplying explosive fluid, a heater for heating said explosive fluid, and means for increasing the supply of explosive fluid and simultaneously diminishing the heating effect thereon.

18. In combination an internal combustion engine, a carbureter for supplying explosive fluid, a heater for heating said explosive fluid and means for diminishing the supply of explosive fluid and simultaneously increasing the heating effect thereon.

19. In a device of the class described, in combination, a carbureter, a throttle valve 20 for governing the supply of explosive mixture from the carbureter, a heater for heating said mixture, a regulating valve for controlling the heating agent for said heater, lever arms for operating said valves, one of 25 said arms having a slot and a rod connected to the other of said arms and carrying a pin working in said slot.

In witness whereof, I have hereunto affixed my signature in the presence of the 30 witnesses herein named.

BURT NEULON PIERCE.
